Primary Examiner — Richard E Chilcot*(74) Attorney, Agent, or Firm* — Hauptman Ham, LLP(57) **CLAIM**

The ornamental design for a ball for sports, as shown and described.

DESCRIPTION

The patent or application file contains at least one drawing executed in color. Copies of this patent or patent application publication with color drawing(s) will be provided by the Office upon request and payment of the necessary fee.

1. Ball for sports

1.1 : Back

1.2 : Left

1.3 : Right

1.4 : Front

1.5 : Bottom

1.6 : Top

This ball for sports shows completely different patterns each other from top view, bottom view, front view and right view; the front view is the same as the back view; the right view is the same as the left view.

1 Claim, 6 Drawing Sheets
(6 of 6 Drawing Sheet(s) Filed in Color)(56)
